UNITED STATES PATENT OFFICE.

OLIVER P. SPILMAN, OF HOUSTON, TEXAS.

MASSAGING MACHINE.

Application filed July 5, 1924. Serial No. 724,303.

This invention relates to new and useful improvements in a massaging machine.

One object of the invention is to provide an exercising or massaging apparatus, specifically designed for use in exercising the trunk and limbs of the human body as an aid in the treatment of disease and for the purpose of reducing the weight of the patient.

Another object of the invention is to provide an apparatus of the character described by which the body may be exercised by a belt or band which is adapted to surround the trunk or limbs of the patient and which is connected to a yieldable oscillating anchor so that the shock or vibration imparted to the body members will be somewhat relieved so as not to be too severe, or injurious.

A further feature of the invention is to provide a device of the character described including means whereby the range of oscillatory movement of the anchor, to which the belt is attached, may be varied so as to regulate operation of the belt.

A still further feature of the invention resides in a novel type of cabinet supporting and partially enclosing the operative mechanism.

With the above and other objects in view the invention has particular relation to certain novel features of construction, operation and arrangement of parts, an example of which is given in this specification and illustrated in the accompanying drawings, wherein:-

Figure 1 shows a vertical sectional view of the device.

Figure 2 shows a vertical sectional view taken at right angles to the view taken in Figure 1.

Figure 3 shows a plan view of the device; and

Figure 4 shows a side view of the belt employed.

Referring now more particularly to the drawings, wherein like numerals of reference designate similar parts in each of the figures, the numeral 1 designates the base of the cabinet which is preferably circular in form, and mounted on this base there is

a tubular housing 2, preferably of about one-half the diameter of the base 1. The housing has a cap like cover 3 fitted onto the top thereof.

Within the housing there is a suitable support 4 having a lateral spindle 5 on which the large gear 6 rotates. Mounted on the base 1, outside of the housing 2 there is an electric motor 7 whose shaft 8 has a small gear wheel 9 fixed thereon and in mesh with the gear 6. The support 4 also carries a lateral spindle 10 on which the connecting rod 11 is pivoted. The lower end of this rod has an oblong lengthwise slot 12 and the gear 6 has an eccentric wristpin 13 which has a bearing in the bearing block 14, mounted to slide in said slot 12.

There is a vertical rocker shaft 15, whose lower end works in the bearing 16 in the top of the support 4, and whose upper end 70 is fitted through the bearing 17 in the cover 3. This shaft has a limited vertical movement in said bearings. Fixed to the shaft 15 there is an oscillating arm 18 whose outer end works through the bearing 19. This bearing is mounted to rotate on a vertical axis in the bearing block 20. This block 20 is slidably mounted in an oblong lengthwise slot 21 in the upper end of the connecting rod 11, and moves back and forth 80 therein as said rod oscillates.

Secured to the upper end of the rocker shaft 15 there is a belt anchor 22 which is formed of flexible material such as spring steel, and is substantially arcuate in plan view. The massaging belt as 23 has its ends attached to the respective ends of this anchor by suitable hooks, or by any other approved fastening means. The middle section of the belt is comparatively wide and 90 preferably formed of rubber or other material which will not abrade the skin of the patient in use.

In operation, the belt 23 is looped around the member of the body to be operated on, 95 and the motor then started. A rocking motion will be thereby imparted to the shaft 15, thus oscillating the anchor 22 and the belt 23. As the belt is drawn tightly around the patient a vibratory or massaging motion 100

will be imparted to the member of the patient which the belt surrounds thus giving the required exercise to said member for the purposes intended.

5 Means have been provided for varying the range of movement of the belt which will now be described. There is an adjusting arm 24, which has a bearing on the shaft 15, but is confined against endwise movement thereon by the fixed collars 25, 25, above and below said bearing. There is an adjusting rod 26 which has a swiveling connection with the cover 3, and whose lower end is threaded through the free end of 15 the arm 24. The upper end of the rod 26 has a crank 27 by means of which it may be turned. By turning the rod 26, the shaft 15 may be adjusted up or down, and the bearing 19 of the arm 18 in the slot 21 20 will be correspondingly moved so as to increase or decrease the throw of said arm and the range of movement of the shaft 15 as well.

The partial rotations of said shaft may 25 be thus varied, in range from zero to about one sixth of a complete rotation, or more if desired. The range of movement of the belt 23 will be correspondingly varied and its vibratory effect can thus be controlled 30 in accordance with the requirements of different patients.

As shown in Figure 3 the ends of the anchor 22 are forwardly curved. In practice these forwardly extending ends will usually 35 be about fourteen inches apart and they will extend forwardly from the shaft 15 about six inches, although these dimensions may be varied, if desired. As the shaft 15 rocks back and forth the forwardly extending ends 40 will swing laterally each way, and will also yield with a snubbing effect on the belt, thus absorbing the shock and preventing sudden jerks and relieving the severity of the exercise.

45 The housing 2 is formed to retain a lubricant and in use will be partly filled with oil so as to submerge the gearing therein.

What I claim is:—

1. In an exercising apparatus a base, a 50 housing mounted thereon, a vertical rocking shaft mounted in the housing and adjustable lengthwise in its bearings, a mechanism enclosed within the housing and including a connecting rod operatively connected with 55 said shaft and adapted to rock the same, an anchor formed of flexible material fastened to the shaft and having its ends free, a flexible member formed into a loop, and having its ends attached to the respective 60 ends of the anchor, and means for varying the relation of said rocker shaft and connecting rod and through which the range of movement of said rocking shaft may be varied.

2. An exercising apparatus including a

base, a housing thereon, a rocking shaft, means in the housing operatively connected to said shaft and adapted to partially rotate the shaft back and forth, an anchor attached to said shaft having its ends free and flexible, a looped belt adapted to pass around the body of the patient and whose ends are fastened to the free ends of the anchor, the ends of said anchor being forwardly turned so as to move back and forth, as the shaft rocks, in front of the plane passing through said shaft and which is normally at right angles to the normal common plane of the patient and shaft so as to impart a side swinging movement to the belt. 70

3. An exercising apparatus including a base, a housing mounted on the base, a cap-like cover fitted on to said housing, a support within the housing, a driving gear mounted on said support, a motor operatively connected with and adapted to drive said gear, a connecting rod pivoted to said support, the lower and upper ends of which are provided with long bearings, an eccentric wrist carried by said gear and operating in said lower bearing, a vertical rocker shaft whose lower end has a bearing in said support, and whose upper end has a bearing in said cover, said shaft having a limited vertical movement in said bearings, an oscillating arm fixed to said shaft and whose free end works in the upper bearing of said connecting rod, an arcuate flexible belt anchor carried by the upper end of said shaft and a belt whose free ends are attached to the corresponding ends of said anchor. 90

4. An exercising apparatus including a base, a housing mounted on the base, a cap-like cover fitted into said housing, a support within the housing, a driving gear mounted 105 on said support, a motor operatively connected with and adapted to drive said gear, a connecting rod pivoted to said support, the lower and upper ends of which are provided with long bearings, an eccentric 110 wrist carried by said gear and operating in said lower bearing, a vertical rocker shaft whose lower end has a bearing in said support and whose upper end has a bearing in 115 said cover, said shaft having a limited vertical movement in said bearings, an oscillating arm fixed to said shaft and whose free end works in the upper bearing of said connecting rod, an arcuate flexible belt anchor carried by the upper end of said shaft, and a belt whose free ends are attached to corresponding ends of said anchor and means 120 connected with said shaft through which it may be adjusted lengthwise in its bearings and its range of movement thereby varied. 125

5. An exercising apparatus embodying a rocking shaft, a means operatively connected with said shaft and adapted to partially rotate the shaft back and forth, an arcuate belt anchor attached to said shaft and hav- 130

ing its ends free, a looped belt adapted to pass around the body of a patient and whose ends are fastened to the respective free ends of the anchor, the ends of said anchor being turned toward the patient so as to move back and forth, as the shaft rocks in front of the plane passing through said shaft and

normally at right angles to the normal plane of the patient and shaft, so as to impart a side swinging movement to the belt.

In testimony whereof I have signed my name to this specification.

OLIVER P. SPILMAN.
